REFUSE RECEPTACLE

Michael Saphier, New York, N.Y., assignor to Lincoln Metal Products Corporation, Brooklyn, N.Y., a corporation

Filed Mar. 19, 1962, Ser. No. 69,314

Term of patent 14 years

(Cl. D58—17)

The FIGURE is a perspective view of a refuse receptacle showing my new design, the essential features thereof being shown in full lines.

I claim:

The ornamental design for a refuse receptacle, substantially as shown and described.
